US00D477841S

(12) **United States Design Patent** (10) Patent No.: **US D477,841 S**
Shimizu et al. (45) Date of Patent: ** Jul. 29, 2003

(54) **INK TANK FOR INK JET RECORDING APPARATUS**

(75) Inventors: **Eiichiro Shimizu**, Yokohama (JP);
Hiroshi Koshikawa, Kawasaki (JP);
Masanori Takenouchi, Yokohama (JP)

(73) Assignee: **Canon Kabushiki Kaisha**, Tokyo (JP)

(**) Term: **14 Years**

(21) Appl. No.: **29/157,626**

(22) Filed: **Mar. 25, 2002**

(30) **Foreign Application Priority Data**

Sep. 27, 2001 (JP) 2001-028182

(51) LOC (7) Cl. **18-02**

(52) U.S. Cl. **D18/56**; 347/86

(58) Field of Search D18/56, 43; 347/86,
347/87, 50, 33, 99

(57) **CLAIM**

The ornamental design for an ink tank for ink jet recording apparatus, as shown and described.

DESCRIPTION

FIG. 1 is a front view of an ink tank for ink jet recording apparatus showing our new design;

FIG. 2 is a rear view thereof;

FIG. 3 is a top plan view thereof;

FIG. 4 is a bottom plan view thereof;

FIG. 5 is a left side view thereof;

FIG. 6 is a right side view thereof; and,

FIG. 7 is a perspective view thereof.
